WATER-SPRAY NOZZLE.

1,418,118.

Specification of Letters Patent.

Patented Nov. 24, 1914.

Application filed April 2, 1914. Serial No. 829,000.

To all whom it may concern:

Be it known that I, ADALBERT W. FISCHER, a citizen of the German Empire, residing in the city and county of Philadelphia, in the State of Pennsylvania, have invented certain new and useful Improvements in Water-Spray Nozzles, of which the following is a true and exact description, reference being had to the accompanying drawings, which form a part thereof.

My present invention consists in an improved spray nozzle primarily devised for, but not necessarily restricted to use in cooling a liquid by spraying it into the atmosphere. The improved nozzle was devised with the especial object in view of increasing the practical efficiency and capacity of spray cooling apparatus of given bulk and cost of manufacture.

20 The general method of cooling a liquid ordinarily requires in practice that the liquid to be cooled should be discharged into the cooling atmosphere in conical jets in order to obtain the fine sub-division of the liquid, and the contact of the sub-divided liquid particles with the air necessary for a sufficient transfer of heat from the liquid to the air.

The improved nozzle comprising my invention is a compound nozzle having a central outlet from which one conical jet is delivered and a surrounding annular outlet from which liquid is discharged in the form of a hollow conical jet, and I so construct and use this compound nozzle that the inner jet is conical in form and substantially conforms in shape to, and nests in the hollow conical jet discharged from said annular outlet. The inner jet may be formed by 30 the liquid to be cooled, in which case the exposed jet surface area will be substantially greater than if the same amount of liquid were discharged in a single jet; or the inner jet may be of air, in which case 40 the inner surface of the outer liquid jet is efficiently subjected to contact with the air, and there is no possibility for the outer hollow liquid jet to become filled with a more or less stagnant mixture of air and 50 vapor at a temperature approximating that of the liquid discharged.

The various features of novelty which characterize my invention are pointed out with particularity in the claims annexed to 55 and forming a part of this specification.

For a better understanding of the invention, however, and of the advantages possessed by it, reference should be had to the accompanying drawings and descriptive matter, in which I have illustrated and described a preferred mode of, and means for carrying out my invention.

Of the drawings: Figure 1 is a sectional elevation of a preferred nozzle construction; Fig. 2 is an end view of the nozzle shown in Fig. 1; Fig. 3 is a sectional elevation of a portion of a water-cooling plant; and Fig. 4 is an elevation of one of the nozzles, and the supply connections thereto, employed in Fig. 3.

In the apparatus shown in the drawings, A represents a structure such as is commonly employed in apparatus for cooling the circulating water of surface condensers or the like. This structure is open at the top and has vertical side walls and a bottom wall A' in the form of an inverted V. Water to be cooled is discharged into the structure A adjacent its lower side edges through compound nozzles E, and the cooled water eventually coming down on the bottom wall A' passes through the ports A' formed in the side walls into collecting troughs B, and is returned to the condensing apparatus or other place of use 85 through the piping C. Each nozzle E comprises an outer shell in the form of a hollow convexly conical body shown as internally threaded at E' for attachment to the supporting fitting D'. Within the outer shell 90 is located a tubular body F comprising a conical portion F' and a cylindrical portion F" leading from the smaller end of the conical portion. The member F is shown as internally threaded at its larger end, as indicated at F' for attachment, in the particular construction illustrated, to a corresponding supply pipe G', which passes through the fitting D' to which the outer shell of the nozzle E is affixed. In the larger end of the 100 annular space e between the nozzle E and the body of the member F are located spiral blades or vanes F', which are shown as formed integrally with the member F. In the conical portion of the passage f 105 through the member F, are mounted a series of spiral vanes or blades F'.

In operation the water to be cooled passes to the passage e of each nozzle E, through the pipe D and the space within the corre- 110

sponding fitting D' surrounding the pipe G', and passes to the passage f through the pipes G and G'. The water passing through each passage e is given a spiral movement 5 by the vanes F⁴ and has its velocity increased in passing through the converging outer portion of the passage e and is discharged at the outlet E² therefrom, with such tangential and axial velocity components as to 10 form a hollow conical jet of finely subdivided particles. The water passing through the passage f is given a spiral movement and has its velocity increased as it travels through this passage and is discharged 15 in the form of a conical jet conforming generally to the form of the surrounding jet issuing through the orifice E². I have found that it is essential for the best results that the two jets be definitely separated 20 and spaced apart adjacent their apices. For this reason I have the discharge end of the member F extending a short distance out of the discharge end of the outer surrounding shell, and I find it highly desirable also 25 to have the projecting portion of the member F surrounded adjacent its end by a circumferential rib F⁶ which aids in separating the two jets adjacent their apices, so that neither of these jets will interfere with the 30 proper formation of the other jet.

The apparatus shown in the drawings may be used without any appreciable change where the fluid passing through the passage f is air and not water. This may be accomplished with the apparatus shown in the drawings, for instance, by simply disconnecting the pipes G and G', in which case atmospheric air will be drawn through the pipe G and passage f by the aspirating 35 effect of the outer water jet, or air under a slight pressure may be supplied to the pipe G' through a supply pipe taking the place of the pipe G in the construction shown. When air is thus supplied to the interior of 40 the hollow conical water jet discharged through the orifices E², the air exerts a substantial cooling effect on the inner surface 45 of said hollow jet and prevents the accumulation in the latter of a more or less stagnant mixture of air and vapor at a temper- 50

ature approximating that of the liquid discharged. Such an accumulation if permitted has the effect of confining the cooling effect of the air on the jet mainly to the outer surface of the jet.

Having now described my invention, what I claim as new and desire to secure by Letters Patent, is:

1. A spray nozzle formed with a central passage terminating at one end in a discharge orifice, and with a surrounding passage terminating at one end in an annular discharge orifice surrounding said central passage and adjacent but slightly back of the discharge orifice of the central passage, 60 and also formed with a rib projecting outwardly from the wall surrounding said central passage between the discharge orifices from the two passages, and means for giving a whirling action to the fluid passing 65 through each passage whereby the fluid is discharged from said central passage in a conical jet and is discharged from said outer passage in a hollow conical jet surrounding 70 the first mentioned jet.

2. A spray nozzle comprising a central tubular portion terminating at one end in a discharge orifice and having a fluid inlet at its opposite end, and a tubular part surrounding the first mentioned tubular part 80 and separated therefrom by an annular space which forms a fluid passage terminating in an annular discharge orifice adjacent the discharge orifice of said central tubular part, one set of spiral vanes located within 85 the first mentioned part, and a second set of spiral vanes located in the annular space between said tubular parts, each set tending to give a whirling action to the fluid passing through the corresponding passage, said central tubular part projecting slightly in front of the discharge orifice from said annular space and being formed with an external circumferential rib separating the jets adjacent the orifices from which they are discharged.

ADALBERT W. FISCHER.
